TYPE WRITING MACHINE.

No. 581,570.

Patented Apr. 27, 1897.

UNITED STATES PATENT OFFICE.

GEORGE KERR ANDERSON, OF BROOKLYN, NEW YORK.

TYPE-WRITING MACHINE.

SPECIFICATION forming part of Letters Patent No. 581,570, dated April 27, 1897.

Application filed January 12, 1897. Serial No. 618,947. (No model.)

To all whom it may concern:

Be it known that I, GEORGE KERR ANDERSON, a citizen of the United States, residing in Brooklyn, in the county of Kings and State 5 of New York, have invented certain new and useful Improvements in Type-Writing Machines, of which the following is a specification.

My invention relates to type-writing machines, and more particularly to that class in which the characters are printed transversely across a continuous strip of paper, and is designed primarily for shorthand-work, though capable of being used for other purposes.

15 The object of my invention is to provide an efficient device of simple construction and operation adapted to rapidly recording speech in the ordinary letters and characters of the alphabet and without resort to any code of cipher 20 combinations, so that the work may be legible to any one without previous study. In furtherance of this object I have provided improved means for feeding the paper and ink-ribbon through the machine in the operation thereof; 25 an improved arrangement of the printing-characters, in groups and otherwise, with reference to each other and with reference to the key-bars; improvements in hanging and shifting groups of printing-characters in machines 30 of this nature; an improved arrangement of the key-buttons and of the letters thereon, and various minor improvements which are 35 fully disclosed in the following specification, of which the accompanying drawings form a part, in which—

Figure 1 is a plan view of my type-writing machine, natural size, the left-hand shift-key B' being broken away to permit the figure to go on the sheet. Fig. 2 is an enlarged detail 40 plan view of the printing mechanism. Fig. 3 is a central longitudinal section on the line 3 3 of Fig. 1. Fig. 4 is a rear view. Fig. 5 is a detail section on the line 5 5 of Fig. 2. Fig. 6 is a detail section on the line 6 6 of Fig. 45 2. Fig. 7 is a detail of the type-segments or type-carrying frames E, E', and E''. Fig. 8 is a detail section taken on the line 8 8 of Fig. 3. Fig. 9 is a detail of the feeding-frame.

A indicates the base-frame, which is provided 50 with the upwardly-directed side plates A² and with curved or segmental plates A³, in which are transverse slots through which

the key-bars for the printing-keys B pass and by which they are held in proper alinement. These printing-bars, preferably sixteen in 55 number, are pivotally connected with a curved rod b, which preferably passes through all of the bars, and under each of the bars is a spiral spring b², (shown plainly in Fig. 3,) which operates to force the key end of said bars upwardly and cause the rear or printing ends thereof to rest on the frame A or a suitable pad w provided for them. The rear ends of these printing-key bars are flattened, so as to present a flat surface to the face of the type, 60 and these flattened ends are substantially in a straight line and at equal distances apart, each bar being located directly beneath one of the type or rows of type on the type segments or frames E E' E'', so that by revolving 65 the segment on its shaft any one of the letters in the line above the bar may be brought into position for printing, as hereinafter described.

At each side of the curved plate A³ are the raised elongations A⁴, similarly provided with 70 slots for the four shift-keys B' B² B³ B⁴. As the rear ends of these shift-keys are always more elevated than the ends of the printing-keys, the surfaces of the elongations A⁴ are correspondingly higher than the plate A³, and 75 preferably both plate and elongations are provided with curved flanges through which the slots pass to form additional guides for the keys and are all cast in one solid piece with the base-frame A, though it will be understood that both plate and blocks might be dispensed with and each key-bar held in an 80 independent holder or fastened in any other suitable manner without departing from the spirit of this invention. It is important, however, that the pivotal points of the shift-keys B' B² B³ B⁴ be on a higher plane than the pivotal points of the printing-keys B, for if the 85 shift-keys are curved upward at the ends where they strike the arms of the type-segments a slight side play of the key in its slot will vary the movement it gives to the type-segment, and thus throw the letters out of line.

Referring to Fig. 1, it will be noticed that 100 the arrangement of the key-buttons C of the printing-keys and C' of the shift-keys permits all the keys to be operated conveniently at the same time without changing the posi-

tion of the hands above the keyboard, and this is an important feature of my invention. The keys to the left of the line 3 3 would be operated by the left hand and those to the right of said line by the right hand. The thumb of the right hand would operate either or both of the keys marked "2 U A" and "3 I W," respectively; the index-finger would operate either or both of the keys lettered "4 L V" and "5 K R," respectively; the next finger keys lettered, respectively, "6 M N" and "7 F D;" the next finger keys lettered, respectively, "8 T S" and "9 S T;" the little finger would operate the single shift-key marked "VOW'S LINE 2," and the outer portion of the palm of the right hand would operate the single shift-key marked "CON'S LINE 2." The left hand is similarly placed with reference to the keys on that side of the keyboard. It will be observed that this arrangement of the keyboard is adapted to the natural movements of the hand. The palm of the hand could not well be shifted from one key to another, and is therefore assigned but one. The little finger does not shift easily, and is therefore given but one key. The thumb moves from side to side more readily than back and forth, and its keys are therefore placed side by side. The other three fingers move back and forth more readily than from side to side, and the keys for them are located accordingly, each pair of keys impinging (but not coming in actual contact) so that both may be simultaneously depressed by putting the fingers where they come almost together.

In lettering the six pairs of finger-keys it will be noticed that the line of key-buttons farthest from the operator have the letters or characters on the left-hand side of each key, while on the lower line of keys the letters or characters are on the right-hand side of each key. It will also be noticed that the key-bar connected with each key on the lower line is to the right of or following each key on the upper line, and this arrangement of letters on the left of the upper key-buttons and the right of the lower key-buttons is for the purpose of indicating to the eye of the operator that each key on the nearer (or lower) line prints to the right of each corresponding key just beyond (or above) it—in other words, that the key lettered "Q M P T" prints immediately to the right of the key lettered "S S S S," &c.

D indicates the shaft on which the type-segments or type-frames E E' E² are mounted. This shaft passes loosely through the uprights A² at each side of the machine, or preferably through the sleeves D⁴ in said upright pieces, and on the left-hand side of the machine the shaft is bent to form a finger-piece, such as D³, while a coiled spring D² causes this bent end of the shaft to bear ordinarily against the stop-pin d² unless it is moved in the operation of the shift-key B³ or is pressed down by the finger against a similar stop-pin

d³ beneath it. The type-frames E and E² are revolvably mounted on the shaft D, while the center type-frame E' is attached to the shaft 70 by a set-screw and moves with it. When at rest, the type-frames E and E² are held against the long stop-pin f by the operation of the coiled springs D' D'.

The center type-frame E', being secured to the shaft D, is held in its normal position by the coiled spring D², which causes the finger-piece D³ to bear upwardly against the stop-pin d², and if the machine is built accurately will also cause the type-frame E' to bear 80 against the common stop-rod f, though this is not necessary. When the three type-frames E, E', and E² are in their normal position against the stop-rod f, the characters shown on the top line of the three type-frames in 85 Fig. 7 would be directly above the flat ends of the printing-key bars B, sixteen in number, one letter facing each bar, so that if the machine were supplied with paper and ribbon and the sixteen printing-keys were struck 90 simultaneously the following letters would be printed across the strip of paper: "STDW CHREAWVRNDST." It will be noticed that these letters appear as the first character in each line or column on the key-buttons C of 95 the respective printing-keys B. To print the letters appearing above them in the various columns, one or more of the shift-keys are used. When the shift-key B² is struck, the outer end travels upwardly until it reaches 100 the shaft D, (or its sleeve,) which acts as a stop, and in rising the shift-key bears against the arm g of the type-frame E, raising it also and revolving the frame until the second longitudinal line of type is brought opposite the 105 flat ends of the printing-keys B. Hence if the sixteen printing-keys B were struck simultaneously with the shift-key B² the following letters would be printed across the strip of paper: "SPBFGLREAWVRNDST." 110

The letters in the third longitudinal line on type-frame E are shifted to the printing-point by depressing the shift-key B' simultaneously with the printing-keys located beneath and opposite the transverse lines of type on frame 115 E, or such of them as the operator wishes to employ; but in this case I use as a stop the flat piece m, made of steel or other suitable material and journaled in the slotted rod l, which is fastened in the frame A² of the machine by a set-screw l' or otherwise. The movable stop m is hung just above the outer ends of the two shift-keys B' and B² and swings freely in its slot, so that normally the lower angle of it, m', will rest against the upper 125 edge of the shift-key B², but the lower edge of the piece m is formed at such an angle that the rising of the shift-key B² will swing the stop m to the right and away from the shift-key B'. Just above the shift-key B' the 130 swinging stop m has a notch or recess m³, adapted to receive the shift-key B' and check its upward movement before it reaches the stop-pin f². This notch m³ is so located that

it will stop the shift-key B' as soon as said shift-key has raised the arm g of the type-frame E sufficiently to bring the third longitudinal line of letters to the printing-point, but when both shift-keys B' and B^2 are struck simultaneously the shift-key B^2 swings the notch m^3 of the stop m out of the path of shift-key B' and allows it to pass on to the stop-rod f^2 , thereby raising the arm g of the type-frame E sufficiently to bring the fourth longitudinal line of characters to the proper printing-point. The coiled spring D' also causes the type-frame E to return to its normal position against the stop-rod f as soon as the shift-key is released.

To bring the second line of characters on type-frame E^2 to the proper printing-point, the shift-key B^4 on the right-hand side of the machine is struck, raising the arm g^2 until the upward movement of the shift-key is checked by the stop-pin f^3 .

The shift-key B^3 , which operates the center type-frame, does not come directly into contact with the frame E' itself, but operates against a projecting portion g^3 of the collar g^4 , which, like the center type-frame E' , is secured to the shaft D by a set-screw or otherwise, so that when a pressure on the shift-key B^3 turns the collar g^4 until the upward movement of the shift-key is checked by the stop-pin f^3 the shaft D and the type-frame E' also revolve until the second longitudinal line of characters on the type-frame E' , namely, "OUI," are brought to the proper printing-point. The coiled spring D^4 operates the type-frame E^2 and the coiled spring D^2 operates the shaft D and thereby the type-frame E' in a manner similar to the operation of the coiled spring D' , already described.

To make numerals, the crank end D^3 , lettered "FIGS.", of the shaft D is depressed until it reaches the stop d^3 , which will bring the numerals on the type-frame E' to the proper printing-point. It will be noticed by reference to Fig. 7 that the three lines of characters on type-frame E' occupy the space of four lines, one intermediate line between the letters and numerals being left blank; also, Fig. 5, that the arm g^3 of the type-frame E^2 curves and passes above the pin g^3 of collar g^4 . Now when the type-frames are all in their normal position resting against the stop-rod f the space between the pin in the collar g^4 and the arm g^2 above said pin will correspond to the movement required at this point for shifting one line of type, thus allowing the pin in the collar g^4 to be raised sufficiently to bring the second line of type on the frame E' into proper printing position without disturbing the arm g^2 , at which time the row of numerals on frame E' is in line with the row of numerals on frame E^2 . Now if the pin g^3 in the collar g^4 is moved any farther it carries the arm g^2 of the type-frame E^2 with it, so that the depression of the crank or finger-piece L^3 of the shaft D will move both type-frames E' and E^2 simultaneously and bring the numerals

on both type-frames E' and E^2 to the proper printing-point.

My object in leaving a blank space on type-frame E' equal to one line and no more (aside from the need of allowing the two rows on letters on type-frames E' and E^2 , respectively, to have room for shifting without the movement of one frame changing the position of the other) was that the arm g^2 of the type-frame E^2 might act as a stop to check the further movement of the type-frame E' when it had been swung into position for the second line of letters by means of the shift-key B^3 , the arm g^2 thus supplementing the coiled spring D^2 in checking the type-frame E' at the proper printing-point for the second line of letters.

Carrying out the idea of providing supplemental stops to offset the momentum of the type-frames and prevent their flying past the proper printing-points I use the coiled spring f^4 , which fits loosely around the shaft D , one end resting on the stop-rod f and the other end extending forward, so as to strike the edge of the type-frame E^2 as soon as it has been swung upwardly far enough to bring the second line of type to the proper printing-point. Similar devices may be used in connection with the type-frame E . The slots for the shift-keys are all made shallow, so that these bars B' , B^2 , B^3 , and B^4 may rest on the bottoms of their respective slots.

In a machine of this nature, which is worthless unless it can be manipulated more rapidly than the ordinary type-writer, the grouping and arrangement of the printing-characters is of the utmost importance, because the speed of the instrument depends very largely upon the smallness of the total number of keys and the largeness of the total number of letters that can be printed at a single stroke. The object of this invention is to provide means whereby an ordinary word can be printed in letters legible to any one at one stroke or motion of the hands, though for some words two or even more strokes are required. To attain this object, I first provide three groups of characters, one group containing a complete consonant alphabet, another group containing a vowel alphabet, and a third group containing terminal consonants of frequent occurrence. I next put each group of characters on a separate type-frame and arrange them in transverse and longitudinal lines, as shown in Fig. 7, each transverse line being directly above the end of a printing-key bar, as clearly shown in Fig. 8, so that as the type-frame is moved or swung around any letter in a transverse line may be printed by striking the key-bar beneath it; and by this arrangement one printing-key is sufficient for all the letters in one transverse row. In the same way I cut down the number of shift-keys needed by placing the letters also in longitudinal rows, as one shift-key is obviously sufficient to shift all the letters in one longitudinal row on one

of the type-frames, and the grouping of the characters in the manner stated and assigning each group to an independent type-frame enables all the letters in a longitudinal line 5 on one of the type-frames to be printed in line and simultaneously with all the letters in any longitudinal line on either of the other type-frames. The letters in the longitudinal lines on the different type-frames are arranged with reference to each other in the order in which they usually occur in spelling words. Thus the first line on type-frame E reads "STDWCHR," which furnishes the combinations "ST," "SW," "SCH," "SC," 15 "SH," "SHR," "TW," "TH," "THR," "DW," "DR," "WH," "WR," "CH," "CHR," and "STR," which so frequently occur in words.

The shift-keys, being designed to operate 20 simultaneously with the printing-keys, are fulcrumed so as to give them a much shorter stroke than the latter, the purpose being to have the type-frames shift and come to a stop before the printing-keys reach them.

25 To feed the strip of paper through the machine, I provide the feeding-frame H', (shown in Figs. 3 and 4,) which consists of a straight piece of steel or other suitable material placed across and above the outer ends of the printing-key bars and having arms extending to the front part of the side plates A² and pivotally mounted between said side plates and about midway between the shift-keys and the printing-keys on the rod i, which extends through 30 the side plates A², and around which rod is a coiled spring i³, one end of which passes through one of the side plates A² and the other end of which bears upon the feeding-frame H', as clearly shown in Fig. 9, and constantly 35 presses it downward upon the ends of the printing-keys. The arms of the feeding-frame H' are connected near the ends through which the pivot rod i passes by the rod i' for the purpose of stiffening the frame, the rod i' 40 being riveted at each end to the arms of the feeding-frame. The feeding-frame H' is also provided at its outer end with the roller I, journaled in the arms of the frame i², and which should be of sufficient diameter to 45 bring its surface a little lower than the edge of the feeding-frame itself, so that as the rear portion of the feeding-frame is pressed downward by the spring i³, as just described, the roller I will bear upon the ends of the printing-keys. The roller I should be located very 50 close to the edge of the feeding-frame H', so as to leave only a narrow slot or opening i⁴ between them just wide enough to allow the strip of paper to pass freely through it. In 55 fact, a narrow slot or opening made at this point by any means would be sufficient to make the feeding device effective, but a roller is preferable, because it lessens the friction. Just a little above the roller I and parallel to 60 it is the flat cross-bar d, each end of which fits into a vertical slot d⁶ in the side plates A², and a little to the rear of this flat cross-

bar is the rod c, loosely journaled in the side plates A², the central portion of which is bent so as to cause it to project, or it may be left 70 straight and a projection formed by putting on the rod a piece of rubber or any other suitable substance, and this yoke or projection c² of the rod c, by the action of the coiled spring c', is made to press downwardly against the 75 cross-bar d, so that if a strip of paper or similar material be passed upwardly between the two, the projection c² of rod c and the cross-bar d, it will push them apart, but if drawn downwardly it will have a tendency to pull 80 them closer together, and by thus wedging itself in between them check any further downward movement. This device, comprising flat bar d and rod c, constitutes a 85 paper-grip.

When the machine is ready for use, an ordinary type-writer ribbon H of suitable width is attached to and wound around the ribbon-reels F and G alternately, and in passing from one to the other runs beneath the rod i 90 of the feeding-frame H', beneath the type-frames E, E', and E², and through the guide-wire e, attached to the cross-bar d, as shown in Fig. 3. The end of each ribbon-reel F and G is provided with a pulley a³ a³, as shown in 95 the drawings. The roll of paper J', having preferably a wooden core J, is mounted on the hollow spindle K, which is held in position by the support a, as shown clearly in Fig. 3, this supporting-rod a having a rectangular bend at its upper end, so that it may pass loosely through the spindle K. The supporting-rod a at its lower end passes through the frame of the machine A² and is held in 105 an upright position by means of a clamp and thumb-nut a², as shown in Figs. 1 and 2. The roll of paper should fit tightly upon the spindle K, so that as the paper is drawn forward through the machine the spindle will revolve as the roll J revolves, and by passing an elastic belt a' around the end of the spindle K and one of the ribbon-reel pulleys a³, as shown in 110 Figs. 3 and 4, the movement of the paper J' turning the spindle K will produce a corresponding movement in the ribbon-reel and 115 cause the ribbon to wind upon whichever reel the elastic belt a' connects with, and then when nearly all the ribbon has been wound upon one reel it may be reversed and caused to wind back upon the other reel by simply 120 changing the elastic belt a' from pulley a³ of ribbon-reel F to pulley a³ of ribbon-reel G, or vice versa.

The operation of the machine is as follows: The paper J' is mounted on the spindle K and 125 the end of the strip passed through the paper-guide j, thence under the ink-ribbon H, under the pivot-wire i of the feeding-frame H', also under the roller I of said frame, and up through the slot or narrow opening between 130 said roll and the outer edge of the frame H', and farther up between the flat cross-bar d and the rod c, a portion c² of which presses against the cross-bar d in such a way as to

form a clutch and prevent the downward movement of the paper between the rod *c* and the bar *d*, as already described. When one or more of the printing-keys *C* are struck, the 5 flat outer ends of the printing-bars *B* will rise until they strike one or more of the type-frames *E* *E'* *E*², and as they rise will force upward the outer end of the feeding-frame *H'*, and the strip of paper *J*, being held fast 10 between the roller *I* and the bar or bars *B* and kept in an upright position by the proximity of the frame *H'*, is also forced upward between the yoke *c*² of spring-operated rod *c* and the cross-piece *d*, the upward movement of 15 the paper having a tendency to push the projecting portion *c*³ of the rod *c* away from the cross-piece *d*, and thus allow the paper to pass more easily. When the fingers are removed from the finger-pieces *C*, the flat ends 20 of the bars *B* drop down to their normal position and the spring on the feeding-frame *H'* forces that down also; but as soon as the strip of paper that is between the rod *c* and the cross-piece *d* begins to descend it draws the 25 yoke *c*² of the rod *c* down more tightly against the cross-piece *d*, and thus the downward movement of the paper is prevented, and the roller *I* of the feeding-frame *H'*, still pressing on the strip of paper, causes enough of it to 30 unwind from the block *J* to allow the feeding-frame to descend to its normal position on the bars *B*, thus presenting a fresh surface for printing upon.

The type-carrying frame *E* has the following letters:

35 STDWCHR (formed without use of any shift-key.)

SPBFGLR (formed by using shift-key *B'* with keys *B*.)

40 SMNVKLY (formed by using shift-key *B*² with keys *B*.)

SQZXJ, (use shift-keys *B'* and *B*² simultaneously.)

45 The type-carrying frame *E'* has the following:

EAW (formed without use of any shift-key.)

OUI (use shift-key *B*².)

50 123 (hold down finger-piece *D*³ before striking the printing-keys *B*.)

The type-carrying frame *E*² has the following:

55 VRNDST (formed without use of any shift-key.)

LKMFTS (use shift-key *B*⁴.)

456789 (hold down finger-piece *D*³ before striking keys *B*.)

60 In writing the shift-keys and printing-keys are struck simultaneously, and as many letters as possible, usually an entire word, unnecessary letters being omitted, should be printed at one stroke, when the machine will automatically move the paper to the next line in the manner already stated. The sentence

"He who runs can read" would appear as follows on the strip:

H	E	
W	H	O
	R	U
C	A	N
REA		D

70

I claim as new and wish to secure by Let- 75 ters Patent—

1. In a type-writing machine, two lines of key-buttons arranged one in front of the other, one row having its letters on the left side of the buttons, the other on the right 80 side, to indicate the order in which the corresponding letters will be printed when the keys are struck.

2. In a type-writing machine a series of keys arranged to print side by side and having 85 their corresponding key-buttons arranged in lines one behind the other and lettered to the left or right of the center of the button.

3. In a type-writing machine a series of keys arranged so as to print side by side simultaneously and having their key-buttons arranged in pairs 90 and having their key-buttons arranged in pairs, one pair for each thumb or finger, and the pairs in curved lines corresponding to the positions of the fingers and thumbs in the act of striking, in combination 95 with shift-keys adapted to operate simultaneously with any printing-key.

4. In a type-writing machine a series of keys arranged so as to print simultaneously and having their key-buttons arranged in pairs 100 in close proximity, one pair for each of the thumbs, arranged side by side, and other pairs for the fingers arranged one behind the other, the several pairs so grouped as to conform to the natural position of the hand in 105 the act of striking the keys, in combination with shift-keys adapted to operate simultaneously with any printing-key.

5. In a type-writing machine, a plurality of shift-keys and a plurality of printing-keys 110 adapted to act simultaneously with and independently of each other, the shift-keys being fulcrumed on a higher plane than the printing-keys, so as to afford a substantially straight shift-key.

6. In a type-writing machine, a plurality of shift-keys and a plurality of printing-keys adapted to act simultaneously with and independently of each other, the shift-keys being fulcrumed so as to have a shorter stroke than 120 the printing-keys.

7. In a type-writing machine a series of printing-keys arranged in two fields, one for each hand, in combination with a plurality of shift-keys adapted to be operated by a single 125 hand simultaneously with any printing-key of one of the fields.

8. In a type-writing machine, a plurality of shift-keys in combination with a movable stop, one of the shift-keys having its movement limited by said stop; the second shift-key being adapted to move the stop out of the 130

path of the first, so that the simultaneous depression of both keys permits one of them to travel farther than when struck alone.

9. In a type-writing machine, a plurality of 5 shift-keys, a movable type-carrying frame and a movable stop for the shift-keys having the lower angle m' and so arranged that the simultaneous depression of both keys will move the type-frame to a different point from 10 that to which it would be moved by the depression of either key singly.

10. In a type-writing machine, a series of 15 key-bars having their rear ends arranged side by side, a spring-operated feeding-frame 20 adapted to press the paper down upon the ends of said bars and grip it, and having a transverse opening at the rear to permit the upward passage of the paper, in combination with a paper-grip above said opening to prevent the backward movement of the paper 25 after it has been pushed through said paper-grip.

11. In a type-writing machine, a series of 25 key-bars arranged side by side and a spring-operated feeding-frame provided with a roller 30 adapted to press the paper against the ends of said bars.

12. In a type-writing machine, a spring-operated feeding-frame provided with a transverse slot or opening, in combination with a 35 paper-grip located above said slot and adapted to permit the passage of the paper away from the feeding-frame and check its movement in the opposite direction.

13. In a type-writing machine, the combination of a plurality of key-bars and a type-carrying frame mounted above the ends of 40 said key-bars on a shaft at one end of which is a crank or handle adapted to turn the shaft and swing the type-frame out of its normal position.

14. In a type-writing machine, the combination of a plurality of key-bars and a type-carrying frame mounted above said key-bars 45 on a shaft whose movement governs the movement of the type-frame, and at one or both ends of which shaft is a lettered crank or finger-piece.

15. In a type-writing machine, the combination of a plurality of key-bars and a type-carrying frame suitably supported above the 50 ends of said bars (or some of them) and having characters arranged thereon in transverse and longitudinal lines, one longitudinal 55 line being separated from the rest by a blank space substantially equal to that occupied by one line of characters.

16. In a type-writing machine, a plurality of key-bars and a plurality of type-carrying 60 frames mounted on a shaft above said key-bars, one of said type-frames being fixed to the shaft and moving with it, in combination with a shift-key adapted to move the type-frame by moving the shaft.

17. In a type-writing machine, a swinging 65 type-frame provided with an arm or projection at its side, in combination with a shift-

key adapted to operate directly against said arm and shift the type.

18. In a type-writing machine the combination of a plurality of key-bars and a plurality of type-carrying frames mounted on a shaft above said key-bars, one of said type-frames being provided with a stop-pin so adjusted that when the frame is moved beyond a certain point, it will carry the other frame with it. 75

19. In a type-writing machine the combination of a plurality of type-carrying frames having arms or pins for the shift-keys to act upon, the arm of one type-frame being so arranged that it will act as a stop to check the movement of another. 80

20. In a type-writing machine, the combination of a plurality of key-bars the rear ends of which are provided with a flat surface and a type-carrying frame mounted above the ends of said bars and adapted to move the type backward and forward, the key-bars being adapted to strike against the type. 85

21. In a type-writing machine, the combination of a plurality of key-bars the rear ends of which rest side by side and a type-carrying frame located above the rear ends of said key-bars, provided with type located opposite the ends of the respective bars and adapted 95 to be struck thereby, said type-frame being adapted to move the type backward and forward above said bars.

22. In a type-writing machine, the combination, with a suitable main frame provided 100 with suitable key-bars and keys, of three swinging type-frames, the central frame being provided with vowels and the side frames being provided with consonants, said vowels and consonants being arranged in longitudinal and transverse rows on each of the three frames, and means for shifting said frame so that a given longitudinal row of consonants may be brought into line with a given longitudinal row of vowels and means to print any number of selected characters in the longitudinal row of each frame. 105

23. In a type-writing machine, the combination with a plurality of keys and key-bars, of a plurality of movable type-frames, each 110 of said frames being provided with letters or characters arranged in both longitudinal and transverse rows, and means for printing any number of selected characters in one longitudinal row simultaneously with any number 115 of selected characters in any other longitudinal row.

24. The combination in a type-writing machine provided with a plurality of keys and key-bars, of a movable type-frame provided 120 with a general alphabet of consonants arranged in a plurality of longitudinal and transverse rows; another movable type-frame provided with frequently-used terminal consonants similarly arranged, and a third movable type-frame located between the other type-frames and provided with a plurality of rows of vowels, and means for shifting said frames so that a given longitudinal row of 125 130

- consonants may be brought into line with a given longitudinal row of vowels and means to print any number of selected characters in the longitudinal row of each frame.
- 5 25. In a type-writing machine, the herein-described arrangement of letters or characters, which consists in separating the consonants from the vowels and putting a general consonant alphabet all on one frame; the 10 vowels on another frame and the terminal consonants on a third frame, so that one shift-key can move an entire group of letters; said type-frames having separate shift-keys provided for each so that all may be moved 15 simultaneously and independently of each other, and means to print any number of selected characters in any longitudinal row of any type-frame.
26. The herein-described arrangement of 20 letters or characters in a type-writing machine, which consists in placing a group of vowels on one frame and a group of consonants in a plurality of transverse and longitudinal rows on another movable frame, and 25 means for shifting said movable frame and means to print any character in either of the rows of consonants thereon in the same line and at the same time with any of the vowels, substantially as shown and described.
- 30 27. In a type-writing machine provided with a plurality of type-frames, a movable type-frame having characters arranged in both transverse and longitudinal rows thereon, in combination with keys adapted to print 35 simultaneously any number of selected characters in any longitudinal row.
28. In a type-writing machine, the combination with a plurality of key-bars provided at their rear ends with a flat surface, of a 40 type-frame provided with suitable letters or characters and mounted on a shaft which extends transversely above the flattened ends of said bars; the type on the frame being located to correspond to the flattened ends of 45 the bars, and the type-frame being adapted to swing backward and forward, as described.
29. The combination in a type-writer, of a main frame, a plurality of key-bars, a plurality of type-frames provided with letters or 50 characters which are arranged in a plurality of both longitudinal and transverse lines thereon, and means for shifting said type-frames and means to print any number of selected letters or characters in one of the 55 rows on any type-frame simultaneously with any of the letters or characters in one of the rows on any other type-frame.
30. In a type-writing machine, the combination with a suitable main frame, of a plurality of type-frames provided with suitable letters or characters, a series of printing-keys converging toward a common center and the ends of which are arranged side by side 60 beneath said type-frames and are adapted to 65 strike against said letters or characters, and a plurality of shift-keys to move said type-frames.

31. The combination, in a type-writing machine, of a plurality of printing-key bars converging toward a common center and the 70 rear ends of which are arranged side by side beneath the type-frames, and a plurality of swinging type-frames operated by shift-keys arranged at each side of the printing-keys and adapted to be struck simultaneously 75 therewith.

32. The combination in a type-writing machine, of a plurality of key-bars, a frame pivotally supported above and adjacent to one end of said key-bars and one side of which is 80 adapted to bear thereon when the bars are raised and press the paper down upon the bars, and a friction paper-grip above said frame adapted to allow the paper to pass through when the frame is raised but prevent its backward movement when the frame 85 descends.

33. The combination in a type-writing machine provided with a plurality of key-bars, of a spring-operated paper-feeding frame, 90 pivotally supported above and adjacent to the rear ends of said key-bars and one side of which is adapted to bear thereon when the bars are raised, and a paper-grip located above said frame adapted to allow the paper 95 to pass through when the frame is raised and prevent its downward movement when the frame descends.

34. The combination in a type-writing machine, of a suitable main frame, a plurality 100 of key-bars mounted therein, a type-carrying frame supported above the rear ends of said key-bars, and a swinging paper-feeding frame pivotally supported between the said key-bars and the type-carrying frame and one 105 side of which is adapted to press the paper down against the key-bars and prevent the paper slipping while being shoved upward by the raising of the bars.

35. In a type-writing machine, the combination with a suitable main frame, of a plurality of keys and key-bars, a roll of paper mounted in said frame, a paper-feeding frame provided with a transverse slot or opening through which the paper is passed, and pivotally mounted above the ends of said key-bars and the rear end of which is adapted to rest thereon and clamp the paper when the bars are raised, and a type-frame mounted above said feeding-frame, and a shaft which is adapted to support a ribbon which is adapted to be fed beneath said type-frame, said roll of paper being adapted to be fed beneath said feeding-frame and said type-frame, substantially as shown and described.

36. In a type-writing machine, the combination with a suitable main frame, of a plurality of keys and key-bars; means for mounting a roll of paper; a paper-feeding frame pivotally mounted above the ends of said 130 key-bars and the rear end of which is adapted to bear thereon and clamp the paper, and type-frames mounted above said feeding-frame, said roll of paper being adapted to be

fed beneath said feeding-frame and through a paper-grip adapted to prevent its backward movement.

37. In a type-writing machine the combination with a main frame provided at its rear end with vertical side plates and at its front end with curved or segmental flanges, of a plurality of key-bars pivotally supported between said flanges and in vertical grooves or recesses formed therein, a spring-operated paper-feeding frame mounted between said side plates, the rear end of which is adapted to bear upon the rear ends of said key-bars, and spring-operated type-frames suitably supported above said feeding-frame and suspended therethrough said type-frames being provided with the necessary type, substantially as shown and described.

38. In a type-writing machine provided at its rear end with vertical side plates and at its front end with curved or segmental flanges, a plurality of key-bars pivotally supported between said flanges and in vertical grooves or recesses formed therein, a spring-operated paper-feeding frame mounted between said side plates and the rear end of which is adapted to bear upon the rear ends of said key-bars, and spring-operated type-frames suitably supported above said feeding-frame and suspended therethrough, said type-frames being provided with necessary type and said main frame being also provided with means for supporting an ink-ribbon and for feeding the same beneath said type-frames, and also with means for supporting a roll of paper and for feeding the same beneath said ink-ribbon and said type-frames, substantially as shown and described.

39. In a type-writing machine the combination of a plurality of key-bars, a paper-feeding frame pivotally supported above and adjacent to the rear ends of said key-bars and adapted to bear thereon when the bars are raised, and a device to prevent the backward movement of the paper after it has been fed forward by said frame, consisting of a transverse plate supported just above the ends of said key-bars and a spring-operated rod adjacent thereto and provided with a yoke adapted to bear thereon, substantially as shown and described.

40. In a type-writing machine, the combination of a plurality of key-bars, a paper-feeding frame pivotally supported above and adjacent to the rear ends of said key-bars and adapted to bear thereon, and a device to prevent the backward movement of the paper after it has been fed forward by said frame, consisting of a transverse plate supported just above the ends of said key-bars and a spring-operated rod adjacent thereto and adapted to operate in connection therewith, substantially as shown and described.

41. The combination in a type-writer, of a suitable main frame, a plurality of key-bars and a plurality of type-frames provided with letters or characters which are arranged in

different longitudinal and transverse rows thereon, and means for shifting said type-frames so that the letters or characters in either of the longitudinal rows thereon may be printed, consisting of keys and corresponding key-bars arranged at the side of the frame of the machine and adapted to operate in connection with arms which are connected with the type-frames, and said key-bars being provided with keys, the number of key-bars being equal to the number of the transverse rows of type on the type-frames, substantially as shown and described. 80

42. The combination in a type-writer, of a suitable main frame, a plurality of key-bars and a plurality of type-frames with letters or characters arranged in both transverse and longitudinal rows thereon, so that the letters or characters in either of the longitudinal rows on one frame may be printed in line with the letters or characters in either of the longitudinal rows on any other frame by simultaneously depressing the proper printing-keys and shift-keys; the printing-keys having their key-buttons arranged in pairs and the pairs located to conform to the position of the hands in the act of striking the keys, and the shift-keys having their key-buttons located on either side of the keyboard formed by the printing-keys and in position to be conveniently struck by the hands while operating the printing-keys. 90

43. The combination, in a type-writing machine, of a suitable main frame, a plurality of key-bars suitably supported, and a plurality of swinging type-frames each of which is provided with a plurality of rows of letters or characters which said bars are adapted to strike, and a plurality of shift-keys adapted to operate said type-frames independently of the printing-keys, said shift-keys and said printing-keys being adapted to be operated simultaneously, substantially as shown and described. 100

44. In a type-writing machine, a plurality of movable type-carrying frames each of which is provided with a plurality of letters or characters which are arranged in longitudinal and transverse rows thereon, and a series of printing-key bars corresponding in number with the transverse rows of characters or letters on the type-carrying frames, substantially as shown and described. 110

45. The combination in a type-writing machine, of a swinging type-frame provided with a plurality of rows of type arranged in longitudinal and transverse rows, a shift-key bar adapted to swing said frame independently of the printing-key bars, and printing-key bars arranged side by side and adapted to print simultaneously against the type in either of said longitudinal rows, said key-bars equaling in number the transverse rows of type on the type-frame, substantially as shown and described. 120

46. The combination in a type-writing machine, of movable type-frames, each of which

is provided with a plurality of rows of type arranged in longitudinal and transverse lines and a series of printing-keys arranged side by side in positions corresponding with the 5 transverse rows of type on the type-frames, and adapted, as the frame is moved from one point to another, to bear against any letter in

the transverse row facing said keys, and means for moving said type-frames, substantially as shown and described.
